DENTAL CASTING MACHINE

Filed Feb. 16, 1929

UNITED STATES PATENT OFFICE

JOHN ADAM PHILLIPS, OF WOODSIDE, NEW YORK, ASSIGNOR TO BURNS DENTAL CASTING MACHINE COMPANY, INC., OF FLUSHING, NEW YORK, A CORPORATION OF NEW YORK

DENTAL CASTING MACHINE

Application filed February 16, 1929. Serial No. 340,354.

This invention relates to dental casting machines such as are used by dentists in casting plates, bridges, inlays or other restorations.

In machines of the character specified, a cap is used for closing the flask in which the casting is to be formed and compressed air is admitted to the cap for the purpose of insuring a perfect casting and forcing the metal into all portions of the mold cavity.

10 The invention has for its salient object to provide a simple and practical construction of casting machine of the character specified and, furthermore, a machine capable of adjustment for use with different sizes of flasks.

15 Another object of the invention is to provide a machine of the character specified, so constructed and arranged that the cap which fits over the top of the flask can readily aline itself with the plane of the upper edge of the 20 flask body.

Further objects of the invention will appear from the following specification taken in connection with the drawings, which form a part of this application, and in which

25 Fig. 1 is an elevational view, partly in section, showing a casting machine constructed in accordance with the invention;

Fig. 2 is a sectional elevation taken substantially on line 2-2 of Fig. 3;

30 Fig. 3 is a transverse sectional elevation taken substantially on line 3-3 of Fig. 2;

Fig. 4 is a sectional elevation taken through the cap or cover which fits over the top of the flask; and

35 Fig. 5 is a sectional elevation similar to Fig. 3 but showing the air valve, for admitting air to the flask, open.

The invention briefly described consists of a casting machine having a support for a 40 flask and a cap adapted to fit over the top of the flask. The cap is connected through suitable valve mechanisms to a compressed air supply, and means is provided for pressing the cap against the top of the flask and admitting 45 air to the flask to force the gold or other metal being cast into the cavity of the desired conformation in the flask. The means for moving the cap is so constructed and arranged as to provide a strong leverage and, further- 50 more, is so arranged that the cap will auto-

matically adjust itself to a position in alignment with the top of the flask and may be adjusted in such a manner as to be used with flasks of different sizes and heights.

Further details of the invention will appear from the following description.

In the form of the invention illustrated in the drawings, the machine comprises a base 10 on which is mounted a pump 11, a compressed air tank 12, and a supporting base 13 for the flask.

The pump 11 may be of any suitable construction and is connected to the tank 12 by a pipe 14, a valve 15 being included in the connection between the pump and the tank.

The supporting base 13 for the flask has a threaded opening therein in which is threaded a post 16 on which is mounted a table 17. The table 17 is preferably provided with a plurality of openings 18 therethrough.

A dental flask 20 of the usual construction is supported on the table 17 and has an opening 21 in the bottom thereof and an open top having an upper edge 22.

The flask 20 is invested with suitable mold forming material, such as plaster of Paris, and a mold cavity of the desired form and shape is formed in the investiture. Molten metal is placed in the mold cavity and a cap is then placed over the mold and compressed air is admitted through the cap to the mold, thus forcing the molten metal to completely fill the cavity in the flask.

In the form of the invention illustrated, a cap 25 for closing the upper end of the mold 85 is provided with an upwardly extending threaded sleeve 26 which is threaded into a sleeve 27 formed on the lower end of a tube 28. The tube 28 extends upwardly through a collar 29 which is mounted for limited pivotal movement on trunnions 30, which in turn are pivoted in a lever 31.

The lever 31 is pivotally connected at 32 to a block 33, which in turn is slidably mounted on a vertical post 34 carried by the supporting base 13. The lever 31 is also pivoted at the rear end thereof to a pair of links 40 which are pivoted at their opposite ends to a spindle 41 mounted in a block 42 which is threaded on a threaded portion 43 of the post 100

34. The block is vertically adjustable on the post and after being adjusted to the desired height is held from rotation by a set screw 44, the inner end of which enters a slot 45 formed in the post. A lock nut 46 also holds the block in adjusted position.

Any desired form of valve control mechanism may be used in the machine and in the form of the invention shown the upper end 10 of the tube 28 has lateral openings 50 which are adapted to communicate with a chamber 51 formed in a tubular valve casing 52 which is threaded into the upper end of the collar 29. A packing washer 53 surrounds the tubular member 28 and is positioned between the threaded end of the casing 52 and the bottom of the recess in the collar 29 into which the casing is threaded.

The tubular member 28 has a spindle 55 connected to and extending upwardly from the upper end thereof and a collar 56 surrounds the spindle and seats against the upper end of the tubular member 28. A nut 54 is threaded on the spindle 55 and holds the collar 56 in position and a packing washer 60 is preferably interposed between the nut and the collar. A spring 61 is mounted in the casing chamber 51 and seats at one end against the upper end of the casing chamber 30 and at the other end against the nut 54.

When the lever 31 and the cap are not in operative position or, in other words, when the cap 25 is not disposed in engagement with the upper edge 22 of the flask, the tubular member 28 will be pressed downwardly by the spring 61 to the position shown in Fig. 3, in which the lateral openings 50 are closed. However, when the lever is swung downwardly and the cap 25 is pressed against the upper edge 22 of the flask 20, the tube 28 will be forced upwardly, thus placing the ports or openings 50 in communication with the chamber 51. The upper end of the chamber has a tubular extension 65 which is connected by a hose 66 to the compressed air tank 12.

The cap 25 is preferably provided with an annular recess 70 in which is disposed an annular packing 71 of suitable material, such as asbestos fiber. The central portion of the bottom of the cap 25 has an annular wall 72 having a recess 73 communicating with a central opening 74 in which is positioned a thimble 75 having lateral openings 76 at its lower end and a flange 77 at its upper end. The flange 77 seats against the upper end of the threaded sleeve 26 and when the sleeve is threaded into the sleeve 27, the flange of the thimble is securely clamped between the upper end of the sleeve 26 and the end of the opening in the sleeve 27. A packing washer 78 is preferably positioned between the lower end of the sleeve 27 and the upper surface of the cap 25.

The machine operates in the following manner: When a flask having a mold therein

is positioned on the table 17, and the table has been adjusted to the proper height and the block 42 has also been properly adjusted, the lever 31 is swung downwardly to the position shown in dotted lines in Fig. 1, and pressure is exerted thereon, causing the valve ports 50 to communicate with the chamber 51. Air from the compressed air tank will pass through the chamber and valve ports and downwardly through the tube 28 and thimble 75 into the flask. The compressed air from the tank 12 will cause the molten metal in the flask to be forced into the mold cavity, thus completely filling the cavity. Should the operator desire to use a flask of different height, the table 17 or block 42 can be adjusted to properly position the cap 25. The pivotal mounting of the cap in the lever permits the cap to properly align itself with the top 22 of the flask.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A dental casting machine comprising a flask support, a flask on said support, a compressed air supply tank, valved means for conducting air from the tank to said flask and constructed to spray the air into the flask, said means including a pivotally mounted cap adapted to fit over the top of the flask, means for moving said cap into engagement with and away from the flask, said means being effective to open and close the valved means, and means connected thereto for supporting and vertically guiding said moving means.

2. A dental casting machine comprising a flask support, a flask thereon, a cap adapted to fit over and close the upper end of said flask, a valve tube in said cap having perforations adjacent one end for establishing communication with the interior of the flask and connected at its other end to a source of compressed air, a lever, and means pivotally connecting said lever and said cap whereby the lever will move the cap into and out of engagement with said flask, said means and cap being relatively movable to provide a valve action in said tube.

3. A dental casting machine comprising a flask support, a flask thereon, a cap adapted to fit over and close the upper end of said flask, a valve tube in said cap having perforations adjacent one end for establishing communication with the interior of the flask and connected at its other end to a source of compressed air, a lever connected to said cap and adapted to move the cap into and out of en-

gagement with said flask and to open and close the valve of said tube, a link connected to said lever, a vertically adjustable pivot for said link and means connected thereto for supporting and guiding said lever for movement in a vertical plane.

4. A dental casting machine comprising a flask support, a flask thereon, a cap adapted to fit over and close the upper end of said flask, a valved tube in said cap having perforations adjacent one end for establishing communication with the interior of the flask and connected at its other end to a source of compressed air, said cap being recessed adjacent the perforations thereby to deflect the air throughout the flask as it is sprayed, means connected to the cap to move the same into and out of engagement with the flask and to control the valve of the tube, and means for supporting and guiding said last named means.

JOHN ADAM PHILLIPS.
